Des. 200,238
Patented Feb. 9, 1965

200,238

AUTOMATIC GUN

Thomas R. Stuelpnagel, Torrance, Robert E. Brix, Encino,
Robert E. Hyslop, Sherman Oaks, and Robert G. Hunt
and Leonard W. Price, Los Angeles, Calif., assignors to
Hughes Tool Company, Houston, Tex., a corporation
of Delaware

Filed July 8, 1963, Ser. No. 75,693

Term of patent 14 years

(Cl. D30—1)

Des. 200,238

PAGE 2

FIG. 1 is a rear perspective view of an automatic gun showing our new design;

FIG. 2 is a front perspective view of the same side of the gun shown in FIG. 1;

FIG. 3 is a front perspective view of the gun taken from the side opposite of that shown in FIG. 2;

FIG. 4 is a rear perspective view of the same side of the gun shown in FIG. 3;

FIG. 5 is a top plan view of the gun; and

FIG. 6 is a bottom plan view of the gun.

The gun barrels in FIGS. 5 and 6 are fragmentarily shown for convenience of illustration.

We claim:

The ornamental design for an automatic gun, substantially as shown and described.
